UNITED STATES PATENT OFFICE.

FREDERICK MAX PORITZ, OF NEW YORK, N. Y., ASSIGNOR TO STAR CHANDELIER COMPANY, INC., OF NEW YORK, N. Y., A CORPORATION OF NEW YORK.

DESIGN FOR A BAND FOR LIGHTING FIXTURES.

Application filed April 6, 1925. Serial No. 13,030. Term of patent $3\frac{1}{2}$ years.

To all whom it may concern:

Be it known that I, FREDERICK MAX PORITZ, a citizen of Germany, residing in the borough of Manhattan, city and State of New York, have invented a new, original, and ornamental Design for a Band for Lighting Fixtures, of which the following is a specification, reference being had to the ac-

companying drawing, forming part thereof.

The figure is a plan view of a band for a lighting fixture.

I claim:—

The ornamental design for a band for lighting fixtures as shown.

FREDERICK MAX PORITZ.
